United States Patent Office.

ISAAC ERB, OF LANCASTER, NEW YORK.

Letters Patent No. 96,786, dated November 16, 1869.

IMPROVED WASHING-MACHINE.

The Schedule referred to in these Letters Patent and making part of the same.

To all whom it may concern:

Be it known that I, ISAAC ERB, of Lancaster, in the county of Erie, and State of New York, have invented a new and useful Improvement in Washing-Machines; and I do hereby declare that the following is a full, clear, and exact description thereof, which will enable others skilled in the art to make and use the same, reference being had to the accompanying drawings, forming part of this specification.

Figure 1 is a top view of my improved machine, the detachable cover being removed.

Figure 2 is a detail vertical section of the same, taken through the line $z z$, fig. 1.

Figure 3 is a detail vertical section of the same, taken through the line $y y$, fig. 1.

Similar letters of reference indicate corresponding parts.

My invention has for its object to furnish an improved washing-machine, which shall be so constructed and arranged that while washing the clothes quickly, thoroughly, and without injury to the fabrics, it will enable the cover and presser to be turned back out of the tub and out of the way while putting in and taking out the clothes, and which will at the same time allow a steam-tight cover to be applied to the tub; and

It consists in the construction and combination of the various parts of the machine, as hereinafter more fully described.

A is the tub, the front side and two ends of which are made vertical, and the rear side inclined, as shown in fig. 2.

The tub A is supported on legs B of such a length as to raise the said tub A to a convenient height, and is made of such a breadth as to allow the presser to be turned out and the clothes conveniently introduced and removed.

C are the operating levers, the outer ends of which are connected by a round, D, which serves as a handle in operating the machine, and which levers, C, should be of such a length that the round D will be over, or nearly over the upper edge of the rear or inclined side of the tub A.

The other ends of the levers C are pivoted to lugs or bearings E, attached to the upper parts of the ends of the tub A, near the front side of said tub, or to a stationary part, F, of the top or cover of said tub A, by pins G, passing through said lugs or bearings and through the ends of said levers, or through the arms I.

H is the presser, which is a board, plank, or plate, of suitable thickness, and of a length nearly equal to the interior length of the tub A.

The presser H is placed in an inclined position, and its ends are securely attached to the lower parts of the arms I.

The upper ends of the arms I are securely attached to the forward or pivoted ends of the levers C, and the pins G pass through them, as shown in fig. 2.

The arms I are made wide, and the upper parts i of the rear edges of said arms are made upon the arc of a circle, the centre of which is the axis of the pivoting pins G.

By this construction, as the arms I work up and down in operating the machine, they will always fit into the slots in the cover J, so as to leave no open space for the escape of the steam or the spattering out of the suds.

This manner of pivoting arms I, and their shape, enable the presser to be conveniently and easily turned back out of the tub A, so as to be entirely out of the way when putting in and taking out the clothes.

The part J of the cover is hinged at its rear edge to the stationary part F of said cover.

To the under side of the cover J, at or near its ends, are attached arms K; the outer or free ends of which are attached to a cross-bar, L, the ends of which enter and rest in recesses formed in the inner surfaces of the upper edges of the ends of the tub A, or rest upon cleats attached to the inner surfaces of said ends, near their upper edges.

The arms K should be of such a length that when the presser is turned back out of the tub A, the lower parts of the arms I will strike against the ends of the cross-bar L, and raise the cover J with said presser, so that it will drop back by its own weight into the position shown in fig. 2, to serve as a spout to conduct the suds dripping from the presser H back into the tub A.

As the presser is turned into the tub A, a shoulder or edge of the levers C will carry the said cover back to its proper position by striking against the ends of said cover J, or against the ends of the cross-bar L.

M is the detachable part of the cover, which rests upon the arms K, the cross-bar L, and the upper part of the inclined side of the tub A.

N is an ordinary rubbing-board, which may be detachably or permanently attached to the inclined side of the tub A in such a position that it may be conveniently reached for rubbing any parts of the clothes that may require to be rubbed.

To the outer surface of the upper edge of one end of the tub A is attached a narrow shelf, O, having an upwardly-projecting flange, P, attached to its outer edge.

The ends of the shelf O and of the flange P are secured and strengthened by brackets Q, attached to them and to the said end of the tub A.

The device O P Q is designed to receive and support a wringer, so that the said wringer, when attached to the tub A, may be entirely out of the way of the operating parts of the machine, and at the same time

may be in a convenient position, the shelf O and brackets Q serving as a spout to conduct the suds wrung from the clothes back into the tub A.

Having thus described my invention,
I claim as new, and desire to secure by Letters Patent—

1. The combination of the hinged cover J, arms K, and cross-bar L, with the tub A, levers C, and presser-arms I, substantially as herein shown and described, and for the purposes set forth.

2. An improved washing-machine, formed by the combination of the tub A, levers C, handle D, lugs or bearings E, pins G, presser-plate H, arms I, hinged cover J, arms K, cross-bar L, detachable cover M, and device O P Q, with each other, substantially as herein shown and described, and for the purpose set forth.

ISAAC ERB.
